FRANK C. ANDERSON, OF CINCINNATI, OHIO.

SWITCH STAND.

1,413,152.

Specification of Letters Patent. Patented Apr. 18, 1922.

Application filed February 15, 1922. Serial No. 536,796.

To all whom it may concern:

Be it known that I, FRANK C. ANDERSON, a citizen of the United States, residing at Cincinnati, in the county of Hamilton and 5 State of Ohio, have invented certain new and useful Improvements in Switch Stands, of which the following is a specification.

My invention relates to ground-lever parallel-throw switch-stands in general, and 10 more particularly to the kind disclosed and claimed in my Patents No. 1,360,862, dated November 30, 1920, and No. 1,389,730, dated September 6, 1921, and in my co-pending applications, Serial No. 477,228, filed June 13, 15 1921, Serial No. 486,166, filed July 20, 1921, and Serial No. 510,847, filed Oct. 27, 1921, upon which my present invention is an improvement.

Its object, like the switch-stands of those 20 patents and applications, is to combine ease of manual switch-throwing operation with control of the point-rails by a weighted handle, to permit normal operation without excessive vibration of the point-rails, but to 25 permit opening if the switch is run through, without resilient or breakable connections. It is the especial object of the present invention to afford better bearings for the operating parts, thereby increasing the efficiency 30 of my switch-stand in the performance of those functions. Other objects, peculiar to the present invention, as well as in common with those of the mentioned patents and applications, will appear in the course of the 35 ensuing description.

I attain these objects by the device illustrated, for example, in the accompanying drawing, in which—

Figure 1 is a sectional plan view of the 40 switch-stand, the section being on the plane of the line 1—1 of Fig. 2;

Fig. 2 is a sectional front elevation, the section being on the plane of the line 2—2 of Fig. 1;

Fig. 3 is a vertical front-to-rear section on the plane of the line 3—3 of Fig. 1;

Fig. 4 is a perspective detail view of the rack member;

Fig. 5 is a similar view of the pinion 50 member;

Fig. 6 is a similar view of the crank-and-rack bearing block; and

Fig. 7 is a sectional front elevation corresponding to Fig. 2, but showing a modification.

The base of the stand comprises the middle part 1 with feet 2 at opposite ends, extending down to foot-plates 3; the latter having forward extensions with openings 3' reducing the cross-section at the beginning 60 of each extension so that the extension may be cut away if desired, as in my prior inventions before mentioned. This base also comprises the front shaft bearing 4 and the segmental extension 5 at the rear, with the bearing opening 6 down through said extension concentric therewith and in front-to-rear alinement with the bearing 4. Just to the rear of this bearing 4 the base has the depression 7; and at opposite ends of the base 70 middle flat part 1 are upstanding parts with forwardly and rearwardly projecting ears 8 near their tops. The front ears 8 embrace opposite end parts of the front guide-bar 9, and the rear ears 8 similarly embrace opposite 75 end parts of the rear guide-bar 9; these guide bars 9 thus running across the base a considerable distance up from the top of the flat part 1 and respectively near the front and rear sides of the depression 7. 80

The casing comprises the front shaft bearing 10, rear extension with the target-shaft-bearing opening 11, flat top 12 with depressed flat parts 12' at opposite ends, and open bottom, permitting it to be placed 85 down over the interior working parts after the latter have been fully assembled on the base, and to be bolted to the base by means of bolts 13 in ears on the base and casing at opposite sides of the front bearings 4 and 10, 90 and bolts 13' near respective rear corners of the base middle part, through said middle part and through bottom rear flat extensions on the casing at opposite sides of the rear extension of this casing. 95

The handle-lever 14 is adapted to be thrown to one side or the other and to rest on one or the other of the lever-rests 14' projecting up from respective forward extensions of the foot-plates 3, before mentioned. 100 At the free end of this handle-lever 14 is the weight-handle 15 of approved design, and at the other end, preferably forged integral with the handle-lever, is the pinion-shaft 16, lying in the front shaft bearings 4 and 10 and extending back across the depression 7, as in my prior inventions referred to above.

In the example of Figs. 1 to 5, the pinion member 17 is substantially one half of an 110

elliptical gear lying at opposite sides of the major axis of the ellipse, which major axis is alined with the handle-lever 14, lying in the depression 7 with hubs 18 at front and 5 rear against adjacent sides of the depression, and having a lightening recess 17', and being fixed to the shaft 16 by a key-pin 17" and a pin 19 through its hub and through the shaft. Such a pinion member is dis- 10 closed and fully described and claimed in my copending application Serial No. 510,- 847, filed October 27, 1921, above referred to.

The rack member 20 comprises the upper flat middle part 21 and the opposite end 15 parts 22 curved down and outward from this part 21. A series of teeth 23 project downwardly from these parts 22 and the bottom of the flat part 21 to follow a pitch line that is a development of a half revolution 20 of the pinion member 17 from one horizontal position of its major axis to the other. This rack is similar to that disclosed and claimed in the copending application just mentioned, in its tooth arrangement; the 25 teeth here however, being coarser and fewer in the pinion member 17 and in the rack member 20. As here shown, the pinion member 17 has nine teeth and the rack member has eight teeth. It will be understood 30 that the teeth may be of any suitable size and number, according to said application or to the present invention.

The extensions or curved parts 22 are narrower than the space between the front and 35 rear guide-bars 9, and at their ends have heads 24 projecting up with ears 25 at the front and back, with holes 26 that loosely admit the respective guide-bars 9 so that the rack member 20 can slide freely from one 40 side of the stand to the other on these bars 9. The upper flat part 21 projects forwardly and rearwardly somewhat, over the guide-bars 9, and at opposite edges has the front-to-rear upstanding jaws 27, parallel and 45 considerably spaced apart equidistant from the front-to-rear median line of the rack body.

The target-shaft 28 will be understood to be of suitable design in its upper part, to 50 support a target or lamp or other means at any required height; and the intermediate crank 29, of radius suited to the throw of the rack member 20 according to my invention of the co-pending application mentioned, has the hub 30 receiving the target-shaft 28 down through it. The bearing block 31 is rectangular and flat, with a central circular opening, and fits slidingly between the jaws 27 of the rack member 20; 55 and the arm of the intermediate crank 29 has near its front end the downwardly projecting bearing lug 31' fitting snugly in the central circular opening of this bearing block 31, while the target-shaft extends up 60 through and bears in the opening 11 in the

casing, and the lower part of the hub 30 extends down into and bears in the base opening 6, with a flange 32 bearing on the base therearound, supporting the crank 29 at the proper height to work easily with the bearing-block 31 and rack member 20. Pins 33 fix the target-shaft 28 in the crank hub 30. 70

As in my prior invention mentioned, the direct-switch-throwing crank 34 fits up in the opening 6, with teeth 35 engaged in a 75 transverse groove in the bottom of the hub 30, and the target-shaft 28 is tapped into the center of this crank 34. This crank comprises the radially adjustable crank arm 36, connecting with the switch-connecting rod 80 37 by a pin 38. The casing has the rear extension 39 and the bottom flanges 40 to prevent the pin 38 from rising out of place; and the extensions 39 have the slots 41 for placing the pin 38, in assembling the connection. This is disclosed in my prior invention, and claimed in my Patent No. 1,389,730, before referred to; the crank construction, as well as the rack, pinion and intermediate crank combination generally, being disclosed and claimed in my Patent No. 1,360,862, before mentioned. Also, as disclosed and claimed in my co-pending applications, Serial Nos. 486,166 and 510,847, before referred to, the pinion-shaft 16 has a 95 rear bearing pin in the base, which latter has a depression 42; the bearing pin 43 having a head 44 in the depression, and extending forward into a central bore in the shaft 16, through an upward projection of the 100 base (Fig. 3,) and a lock-plate 45 inclining upward and backward, under the head 44 and bearing against the rear end of the depression 42, where it is held down by the flange 32 of the crank hub 30. This locks 105 the pin 43 in bearing position.

The provision for cutting away the foot plates 3 at their openings 3' is to allow latches to be used instead of the lever-rests 14', for main-line use where locking is necessary. 110 The lever-rests 14' are for yard use, where my invention permits latches to be dispensed with, for convenient throwing, and to allow the switch to be run through without breakage or resort to yielding connections; all of which is fully explained in my prior patents and applications before mentioned. The variable-radius pinion and rack combination permits this to be accomplished more effectively, as fully explained in my 120 co-pending application, Serial No. 510,847, before mentioned.

In the modification of Fig. 7, the pinion 17a is circular, and the rack member 20' has a straight series of teeth, as in my Patent 125 No. 1,360,862, before mentioned; the guide-bars 9' being at a suitable height over the depression 7' for the pinion to mesh with the rack, which latter has the raised middle part 21' with the straight end extensions carry- 130

ing the heads 24 embracing the guide-bars 9' in a manner similar to that of the example of Figs. 1 to 5, inclusive.

In either example, the mounting of the 5 rack member 20 or 20' on the guide-bars 9 or 9' affords a much better guidance than the mere resting of the rack member on the tops of pedestals as in my prior inventions mentioned; and this contributes to the ease 10 of throwing manually, and to the completeness of throwing under the impact when the switch is run through in the wrong direction. Also, this guide-bar construction is much lighter than those of my former in- 15 ventions employing pedestals projected up from the base throughout their lengths. This is especially important in the variable-radius stand, such as shown in Figs. 1 to 5, inclusive, where the guiding elements for the 20 rack member must be at a considerable height on account of the greatly increased maximum pinion-member radius. However, it will be seen that it effects some saving in weight in the uniform-radius pinion stand, 25 such as shown in Fig. 7.

Also, in either example, this construction, owing to the different rack-member formation, permits a lowering of the casing top 12 in the end parts 12', making it less bulky 30 and less obstructive to the switchmen who must pass the stand. However, I prefer that the reduced top parts 12' be horizontal as shown, like the main middle part, as less liable to cause slippage of the switchmen 35 who step on the casing; this being an advantage provided in my prior inventions, wherein the casing tops are continuously flat from end to end.

The use of the bearing-block 31, to slide 40 across between the jaws 27 of the rack member, in either example, with the bearing-lug 31' of the crank 29 or crank 29' turning in the central opening of the bearing-block, greatly reduces the frictional resistance and 45 wear due to the relative motions of the crank and rack member; and it insures a close holding of the point-rails by the meshing pinion and rack teeth, thus adding to the effect of the increased weight efficiency in 50 either example under the conditions involved with my prior inventions and with the present examples, as fully set forth in the prior patents and applications all above referred to.

55 Modifications other than those herein exemplified may occur under different conditions. Therefore, while certain constructional details are deemed preferable in connection with my invention, and I have shown 60 and described these rather specifically in elucidating the construction and use of my invention, as is required, I do not wish to be understood as being limited to such precise showing and description, but

65 Having thus fully described my invention,

what I claim as new and desire to secure by Letters Patent is:

1. In a switch-stand, a base comprising a front-to-rear shaft bearing at its front and a depression to the rear of said bearing, a lever 70 with a shaft in said bearing, a pinion fixed on said shaft and lying within said depression, upstanding means on said base near opposite ends thereof, guide-bars having their ends supported on said upstanding means 75 and extending along the front and rear, respectively, of said depression, a rack member sliding on said guide-bars and having teeth on its bottom meshing downwardly with said pinion, a bearing block guided 80 from front to rear on the upper part of said rack member, a crank turning in said base on an upright axis, to the rear of said depression, pivotally engaging with said bearing-block, and means for operatively 85 connecting said crank to a switch.

2. In a switch-stand, mechanism comprising a lever and a spur pinion coaxially connected, bearing-bars extending along opposite ends of said pinion, a rack sliding on 90 said bearing-bars and meshing with said pinion, an intermediate crank operatively related to said rack, a direct switch-throwing crank coaxially connected to said intermediate 95 crank, and means operatively supporting said mechanism.

3. In a switch-stand, mechanism comprising a lever and a spur pinion coaxially connected, a rack meshing with said pinion and having parallel jaws, a bearing-block guided between said jaws, an intermediate crank pivotally engaging with said bearing-block, a direct switch-throwing crank 100 coaxially connected with said intermediate crank, and means operatively supporting 105 said mechanism.

4. In a switch-stand, mechanism comprising a lever and a spur pinion coaxially connected, bearing-bars extending along opposite ends of said pinion, a rack sliding on 110 said bearing-bars and meshing with said pinion and having parallel jaws, a bearing-block guided between said jaws, an intermediate crank pivotally engaging with said bearing-block, a direct switch-throwing crank coaxially connected with said intermediate 115 crank, and means operatively supporting said mechanism.

5. In a switch-stand, mechanism comprising a lever and a spur pinion coaxially connected, a rack meshing with said pinion, an intermediate crank and means to operatively connect said crank to a switch, and means 120 pivotally engaged by said intermediate crank and slidingly engaging said rack.

6. In a switch-stand, a base, a lever and a spur pinion coaxially connected and mounted on said base, a rack meshing with said pinion, guiding means, means on said rack slid- 125 130

ingly embracing said guiding means, and means to operatively connect said rack to a switch.

7. In a switch-stand, a rack member comprising a substantially straight middle part with extensions inclining away therefrom in opposite directions and having teeth on their adjacent sides, said member having longitudinal bearing means on the outer end parts 10 of said extensions.

8. In a switch-stand, a rack member comprising a substantially straight middle part with extensions inclining away therefrom in opposite directions and having teeth on 15 their adjacent sides, a bearing-block guided transversely of said middle part, and a crank pivotally engaging with said bearing-block.

9. In a switch-stand, a rack member with parallel jaws and having means to guide 20 said rack member, a bearing-block guided between said jaws, and a crank pivotally engaging with said bearing-block.

10. In a switch-stand, a base comprising a front-to-rear shaft bearing at its front and 25 a depression to the rear of said bearing, a lever with a shaft in said bearing, a substantially semi-elliptical pinion fixed on said shaft and lying within said depression, upstanding means on said base near opposite 30 ends thereof, guide-bars having their ends supported on said upstanding means and extending along the front and rear, respectively, of said depression, a rack member sliding on said guide-bars with extensions inclining 35 down in opposite directions from its middle and having teeth on their inclined bottoms meshing downwardly with said pinion, the major axis of the ellipse of said pinion being substantially alined with said lever and the 40 end teeth of said pinion being substantially near the minor axis of said ellipse and meshing with the lower end parts of said rack member at opposite ends of its throw, parallel front-to-rear jaws extending up from the 45 top of said rack member, a bearing-block guided between said jaws, a crank turning in said base on an upright axis, to the rear of said guide-bars, pivotally engaging with said bearing-block, and means for operatively 50 connecting said crank to a switch.

11. In a switch-stand, a base comprising a front-to-rear shaft bearing at its front and a depression to the rear of said bearing, a lever with a shaft in said bearing, a substantially 55 semi-elliptical pinion fixed on said shaft and lying within said depression, upstanding means on said base near opposite ends there-

of, guide-bars having their ends supported on said upstanding means and extending along the front and rear, respectively, of said depression, a rack member sliding on said guide-bars with extensions inclining down in opposite directions from its middle and having teeth on their inclined bottoms meshing downwardly with said pinion, the major 60 axis of the ellipse of said pinion being substantially alined with said lever and the end teeth of said pinion being substantially near the minor axis of said ellipse and meshing with the lower end parts of said rack member 65 at opposite ends of its throw, and means for operatively relating said rack member to a switch.

12. In a switch-stand, a base comprising a front-to-rear shaft bearing at its front and a depression to the rear of said bearing, and upstanding means on said base near opposite 70 ends thereof, alined with said depression and having means on their upper parts in transverse planes to the front and rear, respectively, of said depression, for supporting guide-bars across said base.

13. In a switch-stand, a base comprising a front-to-rear shaft bearing at its front and a depression to the rear of said bearing, an upward extension to the rear of said depression, a second depression to the rear of said upward extension, a lever with a shaft in said bearing, a pinion member fixed on said shaft and lying within the first mentioned depression, a rear bearing pin in said upward extension and extending into said shaft, upstanding means on said base near opposite 85 ends thereof, guide-bars having their ends supported on said upstanding means and extending along the front and rear, respectively, of said first mentioned depression, a rack member sliding on said guide-bars and having teeth meshing downwardly with said 90 pinion, and means for operatively relating 95 said rack member to a switch.

14. In a switch-stand, a base comprising a front-to-rear shaft bearing at its front and a depression to the rear of said bearing, an upward extension to the rear of said depression, and a second depression to the rear of said upward extension, and upstanding means on 100 said base near opposite ends thereof, alined with the first mentioned depression and having means on their upper parts in transverse planes to the front and rear, respectively, of said first mentioned depression, for supporting 105 guide-bars across said base.

FRANK C. ANDERSON.
